UNITED STATES PATENT OFFICE.

CHARLES LENARDIC, OF CLEVELAND, OHIO.

SELF-LEVELING FURNITURE.

1,414,291.

Specification of Letters Patent. Patented Apr. 25, 1922.

Application filed August 14, 1919; Serial No. 317,501. Renewed October 6, 1921. Serial No. 505,926.

To all whom it may concern:

Be it known that I, CHARLES LENARDIC, a citizen of the United States of America, residing at Cleveland, in the county of Cuyahoga and State of Ohio, have invented certain new and useful Improvements in Self-Leveling Furniture, of which the following is a specification.

The primary object of the present invention resides in the provision of self leveling furniture especially adapted for use upon ships in which a platform section such as a table top or chair bottom is adapted to assume a horizontal position at all times regardless of the position of the ship's floor for supporting the same.

A further object of the invention is to provide self leveling furniture for ships in which a table top or chair bottom is adapted to assume a horizontal position at all times while a slight rotary movement of the table top or chair bottom will be permitted with devices for limiting the rotary movement.

With the above general objects in view and others that will appear as the nature of the invention is better understood the same consists in the novel construction, combination and arrangement of parts hereinafter more fully described and then claimed, reference being had to the accompanying drawing by like characters designating corresponding parts throughout the several views, and in which drawing,

Figure 1 is a vertical cross sectional view of a ship's table constructed in accordance with the present invention, and

Figure 2 is a detail perspective view, of the table with the legs broken away and with the table top removed, illustrating the attaching prongs carried by the table supporting member and the cooperating means for limiting the rotary movement of the table top.

Describing the invention more in detail, it being understood that the present construction of self leveling devices may as well be employed in connection with chairs or other forms of furniture, there is illustrated a table embodying supporting legs 3 carrying feet 4 at the lower ends thereof by which the same may be secured to a floor or other support as illustrated. The legs 3 converge upwardly and carry at the upper ends, a bowl-shaped socket member 5 having a relatively large opening which is centrally arranged in the bottom thereof as illustrated

in Fig. 1, while the bowl-shaped member is supported at its upper peripheral edge by the supporting legs 3.

A table top 7 is carried by a cup-shaped member 8 carrying radially disposed prongs 9 at the upper edge thereof and by which the table top 7 is secured to the cup-shaped member 8 as illustrated in Fig. 1.

Ball races are formed in the inner wall 65 of the bowl-shaped member 5 and into which a plurality of ball bearings 10 are adapted to be received, the balls freely supporting the cup-shaped member 8 for unrestricted free movement relative thereto, the balls being retained in the races by the particular formation thereof.

A weight is associated with the cup-shaped member 8 and includes a relatively large casing 11 having a door opening 12 75 through which a desired number of weighted members 13 may be introduced to the casing 11, a screw 14 being carried by the upper end of the casing 11 freely projecting through the relatively large opening 6 and 80 threaded through the centrally formed boss 15 in the bottom of the cup-shaped member 8 and retained adjusted relative thereto by the nut 16.

Means is provided to permit a slight rotary movement of the table top 7 and includes cooperating devices carried by the members 5 and 8, a plurality of angle brackets 17 being secured to the outer wall of the cup-shaped member 8 with outwardly directed forked projections 18 overlying and projecting beyond the upper edge of the bowl-shaped member 5, and between which forked projections, a spur 19 carried by the outer wall of the bowl-shaped member 5 is 95 adapted to extend for free positioning therebetween.

With the construction above described, the table top 7 is capable of being maintained in a substantially rigid position when in use 100 by regulating the contents 13 in the casing 11 while the equilibrium thereof is maintained by the weighted casing associated with the cup-shaped member 8 and freely projecting from the bowl-shaped member 5, 105 the ball bearings 11 permitting a free and unrestricted relative movement of the parts 5 and 8 while the forked projections 18 and the spurs 19 will control the slight relative rotary movement of the table top 7. 110

While there is herein shown and described the preferred embodiment of the invention,

it is to be understood that changes may be made in the device when operatively constructed which will not deviate from the scope of the invention and subject matter 5 claimed.

What I claim is:—

A ship's table comprising cooperating members, one arranged within the other, ball bearings holding the members in spaced 10 relation, a self-leveling weight fixed to the inner member and freely projecting through the outer member, fork-shaped pro-

jections carried by the inner member at points adjacent the upper end thereof and overlying the upper edge of the outer member, and spurs carried by the outer member and projecting upwardly above the edges of the outer member and loosely extending into the fork-shaped projections for limiting the rotary movements of the cooperating members. 15 20

In testimony whereof I affix my signature.

CHARLES LENARDIC.
